UNITED STATES PATENT OFFICE.

GEORGE A. STEINER, OF SALT LAKE CITY, UTAH, ASSIGNOR TO STEINER SALES COMPANY, OF SALT LAKE CITY, UTAH, A CORPORATION OF UTAH.

TOWEL-FOLDING MACHINE.

Application filed May 19, 1924. Serial No. 714,405.

The object of this invention is to provide a machine in which a towel of the roller type can be unwound from its roll and folded into a series of flat folds, one upon the other, 5 preparatory to the washing and mangling operation.

A further object is to provide a towel folding machine by means of which a single attendant can easily and quickly fold the 10 towel web into a series of folds of varying length dependent upon the stroke of the reciprocating member of the folder.

Other objects of the invention will appear from the following detailed description:

15 In the accompanying drawings forming a part of this specification,

Figure 1 is a perspective view of a towel folding machine embodying my invention;

10 Figure 2 is a longitudinal sectional view 20 of the same;

Figure 3 illustrates a mechanism by means of which the folding slide may be reciprocated to effect an automatic folding of the towel web.

25 In the drawing:

2 represents a suitable top having supporting legs 3 and a track 4 for a reciprocating slide 5 having wheels 6 to run on said track. A hand grip is provided at one 30 end of the slide by means of which the operator may grasp and reciprocate the slide back and forth on the top of the table. 8 is a trough extending transversely of the table top and supported by suitable means 35 such as upright standards 9. This trough is adapted to receive the roll 10 of soiled toweling. A roll 11 having a sanded surface as indicated in Figure 1, is mounted in the standards 9 and has a pulley 12 driven 40 through a belt 13 from a suitable source of power, such as a motor 14. The loose end of the towel roll 10 is laid upon this roll 11 and as the roll is revolved the towel is fed thereon and deposited upon the slide 5 45 beneath, and evidently if this slide 5 is in motion the towel will be laid thereon in regular uniform folds, the length of each fold depending upon the degree of reciprocation of the slide. If a long stroke is made,

50 then the folds will be longer, while if the stroke is short the folds will be correspondingly shorter. The towel web is laid smoothly, one fold upon the other, and when the towel has been fully unwound and folded, a cord will be passed around it to hold

the folds together and it is then placed in the washing machine and thoroughly washed and from thence goes to the extractor, and when this operation is finished, the towel still in a folded condition, will be delivered 60 to the mangle, the cord removed and the web fed through the mangle in flattened form; the folds preventing wrinkling and twisting and insuring a smooth even roll when the web emerges finally on the discharge side of 65 the mangle.

If the web of towel is unrolled and put through the washing machine in a loose extended form without any folds, it is almost sure to become twisted so that it has to be 70 straightened out before passing to the mangle. With this arrangement, however, the web of toweling is kept smooth and flat and there is no danger of its becoming twisted or wrinkled before delivery to the 75 ironing machine.

In Figure 3, I have shown a modification which consists in providing a lever 14 pivoted at 15 and having a link connection 16 with the slide 5. A link 17 connects the 80 lever 14 with a crank arm 18 and a gear 19 has a driving connection with the motor 14 and with the crank arm 18 so that when the motor is in operation, a corresponding movement will be imparted to the reciprocating slide to move it back and forth on the surface of the table. In other respects the operation of the device is the same as described with reference to Figures 1 and 2. 85

I claim as my invention:

1. A towel folding machine, comprising a frame, a trough supported transversely thereabove, a driven roller supported adjacent and at a level above said trough and having a roughened surface, and a table reciprocable below the trough and roller, whereby a roll of goods, loosely supported in said trough and having its fabric leading upwardly from the bottom of the trough, over said roller and then vertically downwardly to lie upon the table, is given sufficient area of contact with said roll to obtain a positive feed of the fabric toward the table. 95

2. A towel folding machine comprising a frame, a plate mounted to reciprocate thereon, a trough supported above said plate and adapted to loosely receive and support a roll of toweling, a feed roll having a roughened surface on said roll adjacent to and above 100

110

said trough and over which the loose web of the toweling is placed, revolution of said feed roll operating to unwind the towel web from the bottom of the roll and lay it in folds upon said reciprocating plate, the length of such folds being governed by the degree of reciprocation of said plate.

3. A towel folding machine comprising a frame, a slide mounted to reciprocate thereon, a towel roll support, a feed roll on which the loose end of the toweling web is placed, a motor having a driving connection with said feed roll and mechanism connecting said motor with said reciprocating slide whereby a simultaneous movement will be imparted to said feed roll and slide to feed the towel web and lay it in folds one upon the other upon said slide said mecha-

nism comprising a crank arm geared to said motor, an oscillating lever, a link connecting said crank arm with said lever near its pivot, and a second link connecting said lever with said slide.

4. A device of the class described, comprising a frame, a trough supported transversely thereabove, a roll supported adjacent and at a level above the trough, a table reciprocable below the trough and roller, a lever, a link connecting said lever to said table, and a driving mechanism transmittably connected with the roll, and adapted to oscillate said link.

In witness whereof, I have hereunto set my hand this 13th day of May, 1924.

GEORGE A. STEINER.
